Notification of Grant of Patent Rights for a Design Patent, issued by the State Intellectual Property Office of the P.R. China, in connection with Chinese Patent Application No. 201430416108.X, on Apr. 20, 2015, 4 pages.

Primary Examiner — Holly Baynham*Assistant Examiner* — Rhea Shields(74) *Attorney, Agent, or Firm* — KPPB LLP(57) **CLAIM**

The ornamental design for an electrical plug-in connector, as shown and described.

DESCRIPTION

FIG. 1 is a front perspective view of a power plug.

FIG. 2 is a front side view of the device of FIG. 1.

FIG. 3 is a rear side view of the device of FIG. 1.

FIG. 4 is a left side view of the device of FIG. 1.

FIG. 5 is a right side view of the device of FIG. 1.

FIG. 6 is a top side view of the device of FIG. 1; and,

FIG. 7 is a bottom side view of the device of FIG. 1.

In the drawings, the broken lines are for the purpose of illustrating environment only and form no part of the claimed design.
